UNITED STATES PATENT OFFICE

1,968,492

TOY FIGURE

Joseph L. Kallus, Brooklyn, N. Y.

Application January 28, 1932, Serial No. 589,328

11 Claims. (Cl. 46—40)

My invention relates to toy figures such as dolls, toy animals and the like, and more particularly to jointed toy figures having hollow bodies and other members made of collapsible material such as soft rubber. Because of the inherent yielding or non-rigid characteristics of the soft rubber or its equivalent, considerable difficulty has heretofore been experienced in combining the parts of the figure in a manner to provide an efficient arrangement of joints which will withstand use and permit adjustment of the various parts of the figure in a natural and life-like manner.

The invention has for its object to provide novel constructions in which these difficulties are overcome and in which the body and associated members are connected in jointed relation in a simple and efficient manner. The invention contemplates further the provision of a jointed toy figure, made of hollow soft rubber or its equivalent and constructed in a manner to simulate naturally the relatively rigid and yielding parts of the original which the toy figure is intended to represent. Other more specific objects of the invention will appear from the description hereinafter, and the features of novelty will be pointed out in the claims.

In the accompanying drawings, which illustrate examples of the invention without defining its limits, Fig. 1 is a front elevation partly in section of a doll embodying the novel features; Fig. 2 is a side elevation thereof partly in section; Figs. 3 and 4 are detail sectional views of a novel joint and fastening arrangement forming part of the invention; Fig. 5 is a fragmentary front elevation partly in section of another form of the invention; Fig. 6 is a longitudinal section of the doll shown in Fig. 5 looking at right angles thereto; Fig. 7 is a horizontal section on the line 7—7 of Fig. 6; Fig. 8 is a fragmentary front elevation partly in section of still another form of the invention; Fig. 9 is a sectional view on the line 9—9 of Fig. 8, and Fig. 10 is a detail view of the body of a doll immediately subsequent to the molding thereof.

In the illustrated examples of the invention, the novel features have been shown as embodied in hollow rubber dolls having jointed or relatively movable heads, legs and arms, for which they are particularly adapted; it is to be understood however that the examples shown in the drawings have been selected for illustrative and descriptive purposes only, and that the novel features may be utilized with equal efficiency in connec-

tion with other jointed, hollow toy figures made of collapsible material.

In the form shown in Figs. 1 and 2, the doll comprises a body 15, which is constructed of soft rubber or other equivalent material and is hollow, as shown in the drawings. The doll further includes a hollow head 16 of soft rubber or other suitable collapsible material, said head being adjustably mounted on the body 15 and secured in place thereon by means of conventional elastic cords, bands, or the like 17 attached to a hook 18 carried by the head 16 and serving also to secure the hollow legs 18 of the doll in jointed connection with the body 15 as will appear more fully hereinafter. The hollow arms 19 of rubber or other collapsible material are mounted upon the body in jointed or adjustable relation thereto and are fixed in place by means of elastic cords 20 or the like 20 in the manner to be more fully set forth hereinafter.

Because of the hollow form of the body and other members comprising the doll, and because of the collapsible character of the soft rubber or other equivalent material from which these parts are made, special means is provided to prevent collapse of the doll under the tension developed by the cords 17 and 20 or their equivalent, and to provide an arrangement of joints which will permit the different sections of the doll or its equivalent to be easily adjusted relatively to each other in a natural and life-like manner. In the example shown in Figs. 1 and 2, the means in question comprises a back-bone member, preferably consisting of two tubular sections 21 and 22, suitably connected with each other as by gluing and provided at the lower end with a pelvis member consisting of two complementary sections 23 fastened to the section 22 and to each other in any convenient manner. The pelvis sections 23 are each formed with recesses 24 adapted to receive socket members 25 which, at one end, include annular flanges 26 adapted to clamp the rubber or other material of which the body 15 is made, to the pelvis sections 23. The socket members 25 and the pelvis sections 23 are internally provided with registering openings 27, which terminate at concave recesses 28 formed in the socket members 25; the recesses 28 are dimensioned and constructed to receive the spherical ends 29 of the leg members 18 to provide hip joints on which said leg members 18 may be adjusted at will relatively to the body 15. The normally collapsible or non-rigid spherical ends 29 are internally reinforced by means of reinforcing members or supporting devices 30 illustrated in the form of solid spheres of wood or

other suitable material and provided with fastening devices 31 to which the cords or bands 17 which extend through the recesses 27 are secured. A shoulder section is combined with the back-bone 5 section and consists of tubular socket members 32 fitted into recesses 33 with which the back-bone section 21 is provided, and secured therein in any conventional manner, as by gluing. The socket members 32 are formed at their outer 10 ends with annular flanges 34 and with concave recesses 35 adapted to receive the spherical ends 36 of the arm members 19 to provide shoulder joints on which said arm members may be adjusted relatively to the body 15. To provide the 15 necessary rigidity, the spherical ends 36 are likewise internally reinforced by means of reinforcing members or supporting devices 37 illustrated in the form of solid spheres of wood or other suitable material and carrying fastening devices 20 38 to which the elastic cord or band 20 is fastened, as illustrated in Fig. 1. In addition to the parts so far described, a rigid tubular neck member 39 is mounted upon the back-bone section 21 by means of a reduced continuing section 40, 25 which fits into the section 21 and is secured therein in any well known way. The neck member 39 is formed with an annular recess 41 into which the neck portion 42 of the body 15 extends and in which said portion 42 may be permanently secured 30 in any well known manner. The neck member 39, in the illustrated form, is curved or rounded as indicated at 43 to provide a bearing surface on which the head 16 is adjustably supported and is secured in place by means of the 35 elastic cords or bands 17. The head 16, in the example shown, is also made of hollow collapsible material, such as soft rubber, and in the form illustrated in Figs. 1 and 2 is internally reinforced by means of a rigid interior member or support- 40 ing device 44 which, in its preferred form is also hollow and constructed in a preferred manner to be more fully set forth hereinafter.

In constructing the form of the doll now being described, the body 15 is molded in any conventional manner, for instance, by placing a suitable quantity of uncured rubber of putty-like consistency within a mold and then introducing air or other fluid pressure into said mold to expand the rubber into contact with the molding surface 45 thereof. At the finish of the molding operation, the body is removed from the mold and presents an appearance for instance, as indicated in Fig. 10, said body, in effect, constituting a more or less inflated air bag, all parts of which are closed. 50 In this condition, the body is vulcanized or cured in the conventional manner, or subjected to any other treatment dependent upon the nature of the material from which it is made, to bring it to its final condition for use. In molding the leg members 18 and the arm members 19, the same procedure is followed, with the exception that the internal reinforcing members 30 and 37 respectively, are introduced into the mold after first having been covered with a suitable rubber cement or 55 its equivalent and are molded in place in the leg members 18 and arm members 19, respectively, coincidentally with the molding of said members; the combined members and reinforcing members are then vulcanized. The leg members 18 and 60 the arm members 19 at the end of the molding and vulcanizing operations also comprise hollow more or less inflated flexible elements as indicated, for instance, in Fig. 3, which shows the spherical end 37 of one of the arm members 19; it will be 65 understood that the spherical ends 29 of the leg

members 18 present a substantially similar appearance at the corresponding stage of production.

In order to provide an efficient fastening means for attachment of the elastic cords 17 and 20 or their equivalent, the reinforcing members 37 are provided with recesses 37a and continuing apertures 37b in which fastening devices 38 with their heads 38a are slidably mounted; in the illustrated example, the fastening device 38 is in the form of a hook, the return member 38b of which, during molding and vulcanizing, is located within a recess 37c also provided in the reinforcing member 37, as shown best in Fig. 4. The reinforcing members 30 located within the spherical ends 29 of the leg members are provided with fastening devices 31 of the same general type as the devices 38 and similarly mounted so as to be slidable in said members 30 in the manner described with respect to the reinforcing members 37. During the molding of the arm and leg members, the fastening devices 38 and 31 occupy the position indicated in Fig. 3 in which the return members, such as 38b, are located within the recesses indicated by the reference character 37c, so that all parts of each fastening device are located within the confines of the associated spherical end 36 or 29, as the case may be. After the arm and leg members 19 and 18 respectively have been vulcanized, the reinforcing members 37 and 30, through the medium of the rubber cement coating previously applied thereto have been vulcanized to the respective arm or leg members and thus have been intimately united therewith so as to become substantially integral parts of said arm and leg members, respectively. If found desirable or necessary the reinforcing members 37 and 30, or their equivalents, may extend beyond the spherical ends of the respective arm and leg members into other parts of these members, for the purpose of providing support against collapse 115 to such other parts, or for any other purpose. At the conclusion of the vulcanizing processes, the dome-like or other projections a which remain on the arm and leg members respectively are cut away so as to leave in the spherical members 36 and 29 openings such as the openings 36a and 29a respectively. The hook-ends of the fastening devices 38—31 are thereby rendered accessible and accordingly may be adjusted to the positions indicated in Figs. 1 and 4, in which the return portion, such as 38b has been withdrawn from the recess indicated by the reference character 37c; this adjustment of said fastening device brings the head 38a thereof, or its equivalent into contact with the inner end of the recess 37a to thereby 120 prevent a further withdrawal of said fastening device relatively to the reinforcing members 37 or 30 and brings the hook-ends of said fastening devices into position for connection with the elastic cords 20 and 17 or their equivalent. 125

To complete the doll structure now being described, the doll body is trimmed or cut along the line b to remove the hollow projection c and to leave the body 15 with the annular neck flange 42 previously referred to. In addition, the body 140 15 is further cut or trimmed along the lines d to remove the hollow projections e which results in the formation of shoulder openings and pelvis openings respectively in the body 15. The united back-bone sections 21 and 22 may then be inserted into the interior of the doll body 15, either through the neck opening or one of said pelvis openings, after which the socket members 32 are inserted through the shoulder openings into the openings 33 of the back-bone section 21; the sock- 135 145 150

17a and 20a, which correspond to the elastic cords or bands 17 and 20 respectively, of Figs. 1 and 2. In order to reduce friction to a minimum and to still further facilitate the adjustability of the leg members 18a and arm members 19a, the spherical ends 29a and 36a may be provided respectively with bearing members 45 and 46, which preferably comprise metallic shells of hemispherical form and are secured in position 10 on the respective spherical ends in any convenient manner; the bearing members 45 and 46 are provided with apertures 45a and 46a through which the fastening devices 31 and 38 are accessible for connection respectively with the elastic cords or bands 17a and 20a.

In constructing the doll now being described, the body 15a may be molded, vulcanized or otherwise brought to a finished state and trimmed or cut to produce the various openings in the same 20 way as set forth with respect to the body 15 of Figs. 1 and 2. The back-bone section 21a may then be inserted into the body 15a through the neck-opening thereof or otherwise, and the body material forced into the annular recess 41a 25 and secured therein in any conventional way. As the next step, the socket members 25a may be inserted through the pelvis openings in the body 15a and extended into the recesses 24a of the section 21a in the manner illustrated in Fig. 30 5 and secured in such recess, either by glue or by means of forced fits; if the socket members 25a have been fastened in place on the section 21a, previous to its insertion into the body 15, as may sometimes be done, the said socket members 35 25a are inserted into the pelvis openings from the inside. In either case, the material of which the body 15a is made will engage the annular shoulders 26a with the peripheral surfaces of said openings in engagement with the 40 contiguous surfaces of said socket members. To complete the arrangement, socket members 32a, which may be substantial duplicates of the members 32 of Figs. 1 and 2, are inserted through the shoulder openings of the body 15a into recesses 45 33a formed in the member 21a and corresponding to the recesses 33 of Figs. 1 and 2. The socket members 32a are also provided with annular flanges 34a corresponding to the flanges 34 of Figs. 1 and 2, and likewise engaging the 50 body material surrounding said control openings, as clearly shown in Fig. 5; the socket members 32a may be secured in the recesses 33a by gluing or by simple force fits therein. The sockets 25a are provided with concaved recesses 28a for 55 the reception of the bearing members 45 fixed upon the spherical ends 29a of the leg members, which socket members 32a include concave recesses 35a for the reception of the bearing members 46 secured upon the spherical ends 36a 60 of the arm members 19a. The arm members 19a are fixed in place in the manner previously indicated with respect to Figs. 1 and 2 by the elastic cords or the like 20a, and the leg members 18a are adjustably held in place by means 65 of the elastic cords 17a or the like, which engage a fastening device 18b located interiorly of the head 16a, which is adjustably mounted on the curved surface 43a of the neck section 39a, and is adjustably held in place thereon by the tension 70 of the cords or bands 17a.

The head 16a may be of the same general construction as the head 16 of Figs. 1 and 2, but in the example shown in Figs. 5, 6 and 7 comprises a special construction which will now 75 be described. In this special construction the

head 16a is made of soft rubber or equivalent material and is molded in hollow form in any conventional way, for instance, as previously set forth with respect to the molding of the bodies and leg and arm members described hereinbefore, so that in its normal condition, the head is collapsible and without any inherent rigidity of its own. To provide the desired rigidity against collapse, and to make said head conform more closely to the natural characteristics of the natural head exemplified thereby, a rigid means 16b is located within said head for supporting predetermined portions thereof against inward collapse under external pressures exerted thereon or forces developed internally of the toy figure, for instance, by the elastic cords 17, 17a, or their equivalent. In the illustrated example, this supporting means 16b comprises a hollow device which may be constructed of plastic material, metal or other suitable material and in any case is combined with the head 16a during the molding thereof; that is to say, the device 16b when made of metal or the like, after first having been coated with a rubber cement or other suitable material is introduced into the 100 mold with the material of which the head 16a is composed, which is then molded in the conventional manner; if made of plastic material or the like the device 16b is coated with rubber cement or the like as before, is placed with the 105 head material in the mold so that the head and the device 16b may concurrently be molded to the desired finished shape. After the molding process has been completed, the combined head 16a and the supporting device 16b are vulcanized, 110 so that both become intimately united by vulcanization to comprise, in effect, a unitary structure. The device 16b corresponds in its arrangement and characteristics to the particular head of the toy figure with which it is combined. In 115 the illustrated example, the supporting device 16b comprises a frontal section, a skull section, a back section and a lower portion which is apertured to adjustably fit upon the neck member 39a, as clearly shown in Figs. 5 and 6. The 120 front portion of the device 16b in the form shown in Figs. 6 and 7 is cut away to form a front opening in registry with the face of the doll, and at the sides along a curved line 16c, so that the face of the doll and the cheeks thereof are 125 unsupported from the inside and accordingly are capable of yielding inwardly in a manner closely simulating the face and cheek portions of a natural human head. With this arrangement, the device 16b may serve as a support for the framework 47, which carries the eyes 48 in such a manner that said eyes may operate to simulate the eyes of a sleeping person, and one who is awake. In such case, the head 16a will be provided in the face portion thereof with eye-sockets 130 49 through which the eyes 48 project and in which they are movable, as previously described. With the arrangement now being described, the supporting device 16b may also carry the fastening device 18b which, in such case may be secured to the device 16b by being molded therein and include a head 18c embedded in the device 16b to maintain the fastening device 18b in connection with the device 16b under the tension 135 exerted by the elastic cords 17a or their 140 equivalent.

In some forms of toy figures, it may be desirable to combine the means whereby the body of the figure is supported against collapse in a predetermined manner, by molding the support- 150

ing device within the body coincidentally with 9 of Figs. 1 and 2, or the leg members 18a and the molding thereof in a manner similar to the arm members 19a of Figs. 5 and 6.

method described with respect to the head of Figs. 5, 6 and 7. Such an arrangement embodied in Figs. 8 and 9. When the doll of Figs. 8 and 9 has been completed, the body 15a will be rigidly supported in a doll as illustrated in Figs. 8 and 9. In this form, the doll comprises a hollow body 15b of a manner to correspond to the characteristics of a soft rubber or equivalent material corresponding to a natural human body at the indicated sections; 15b at the conclusion of the molding operations, the upper chest portion of the body and the front 10 may present the appearance illustrated in Fig. 8, supported from within, while the lower chest portion

10. The internal supporting means, as illustrated in Figs. 8 and 9, comprises a back-bone 21b, an unsupported and accordingly will yield in section 21b, a shoulder and chest section 32b, forwardly at the front and sides in approximate and a pelvis section 23a. The section 32b is a simulation of the corresponding parts of a human body.

ings 35c are located, and the pelvis section 23a. It will be understood that the plastic material includes concave recesses 28b in which openings referred to in the specification for use in connection with Figs. 8 and 9, are formed, as shown in Fig. 8. The sections constituting the supporting devices in some forms, 21b, 32b and 23a, comprise integral parts of each other and may be formed of such a character that it will become set or

20 other and may be formed of metal, plastic material or any other suitable substance. The unit properties in its final form.

Similarly, it is to be understood that the application of a rubber

25 made of metal or corresponding substantially to the supporting device, rigid material, after having been covered with a cement or its equivalent, is in some instance be omitted.

introduced into the mold with the material from which the body 15b is made, so that the supports specifically in connection with a toy doll, supporting device now being described is combined, it will be obvious that they may be incorporated 30 with said body 15b during the molding; if said supporting device is made of plastic or other figures will very closely approximate the original similar moldable material, said device, in addition, the internal supporting means

35 of which said figures are copies. In all forms the toy figures accordingly present not

30 manner described above, may be molded to final only a most natural appearance, but embody

shape, coincidentally therewith. After the molding operation has been completed, the combined human or animal bodies constituting the

40 body and internal supporting device are vulcanized originals of the toy bodies under discussion.

45 and thereby become intimately united together. In addition, the internal supporting means

50 in form a substantially unitary element. The doll provides mechanical arrangements which effi-

ciently operate to resist tensional forces inherent

55 corresponding to the neck member of toy figures present in the different types of jointed figures

60 Figs. 1 and 2, and similarly including an annular recess 41 for the reception of the neck portions maintained in their intended relation to each

65 42 with which the body 15b may be provided. In those forms in which the internal sup-

70 porting device is combined with the respective neck portion 42, may be permanently secured in the members or elements of the toy figures by mold-

75 an annular recess 41 in any convenient manner, and subsequent vulcanization, a most intimate

80 the neck member 39 may be fastened in place and efficient union of the parts is secured so that

85 by means of a reduced continuing section 40 fitting into effect the internal supporting means and the

90 inserted into an opening provided in the section 32b members or elements in which said means are

95 secured in such opening in any desirable manner. To complete the doll, a head, either as

100 shown in Figs. 1 and 2, or as illustrated in Figs. 5, 6 and 7 is mounted upon the neck member 39, been recognized as ideal replicas of the originals

105 and secured in place by means of elastic cords from which they are copied. Such toy figures,

110 17b, which serve also to fix the spherical ends, however, up to the present time have lacked the

115 29 of the leg members 18 in the recesses 28b of adjustability inherent in other types of figures,

120 the pelvis section 23a to adjustably secure said which include jointed constructions, because of

125 the fact that said rubber or equivalent dolls and

130 other figures have usually been molded as units in

135 which all parts of the figure are molded together as integral parts. With the present novel

140 constructions, all of the desirable features present

145 in the existing hollow toy figures of soft rubber

150 or the like, and inherent in existing toy figures

155 of jointed construction are included in their en-

160 tirety, with the additional advantage that toy

165 figures constructed in accordance with the instant invention much more closely simulate the

170 originals from which they are copied. The

175 novel toy figures present no particular difficulties of manufacture and are not excessively expensive to produce.

180 members 19 of Figs. 8 and 9 may correspond in

185 various changes in the specific forms shown

190 construction either to the leg and arm members and described may be made within the scope of

the claims without departing from the spirit of the invention.

I claim:

1. A doll comprising a hollow collapsible body, provided with a neck opening and arm and leg openings, a rigid device located interiorly of said body and extending lengthwise thereof, a neck member extending from said rigid device outwardly through said neck opening and connected with said body thereat to constitute a bearing surface exteriorly of said body, said rigid device being provided with arm recesses and leg recesses in proximity respectively with said arm and leg openings, a head movably mounted on the exterior bearing surface of said neck member, arm members movably mounted in said arm recesses, leg members movably mounted in said leg recesses, and means whereby said head, arm members and leg members are adjustably connected with said body.
2. A doll comprising a hollow collapsible body provided with a neck opening, arm openings and leg openings, a rigid device located interiorly of said body and extending lengthwise thereof, a neck member located exteriorly of and connected with said body at said neck opening and projecting inwardly through the same into connection with said rigid device to constitute an external bearing surface, a head adjustably mounted on the bearing surface of said neck member, socket members located exteriorly of said body and extending inwardly through said arm openings into connection with said rigid device to constitute external bearing surfaces, arm members adjustably mounted in the external bearing surfaces of said socket members, additional socket members located exteriorly of said body and extending inwardly through said leg openings into connection with said device to constitute additional external bearing surfaces, leg members adjustably mounted in the external bearing surfaces of said last named socket members, and means whereby said head, arm members and leg members are adjustably secured in connection with said body.
3. A doll comprising a hollow collapsible body, provided with a neck opening and arm and leg openings, a rigid device located within said body and extending lengthwise thereof, a neck member projecting outwardly from said rigid device through said neck opening and connected with said body thereat to constitute a bearing surface exteriorly of said body, a head movably mounted on the exterior bearing surface of said neck member, socket members extending through said arm openings into connection with said device, arm members adjustably mounted in said socket members, additional socket members connected with said device and projecting through said leg openings, leg members adjustably mounted in said last named socket members, and means whereby said head, arm members and leg members are adjustably connected with said body.
4. In a doll, a hollow collapsible body provided with a neck opening and arm and leg openings, a back-bone member located within said body and consisting of two connected tubular sections, a neck member connected with said back-bone member and extending through said neck opening and being connected with said body thereat, socket members extending through said arm openings into connection with said back-bone member and provided with externally accessible concave recesses, annular flanges carried by said socket members and engaging said body ex-

teriorly of said arm openings, a pelvis member consisting of two sections connected with each other and with said back-bone member and provided with recesses in registry with said leg openings, socket members extending through said leg openings into the recesses of said pelvis sections and provided with externally accessible concave recesses, and annular flanges carried by said last named socket members whereby said body is clamped against said pelvis sections adjacent to the peripheries of said leg openings.

5. A doll comprising a hollow collapsible body provided with a neck opening and arm and leg openings, a back-bone member located within said body and extending lengthwise thereof, a neck member comprising an integral extension of said back-bone member and projecting outwardly through said neck opening to constitute a bearing surface exteriorly of said body, said back-bone member being provided with an annular recess at the base of said neck member in which the body at said neck opening is secured, a head movably mounted on the external bearing surface of said neck member, socket members extending through said arm openings into connection with said back-bone member, annular flanges carried by said socket members and engaging said body exteriorly of said arm openings, additional socket members connected with said back-bone member and extending outwardly through said leg openings, said socket members being all provided with externally accessible concave recesses, arm members movably mounted in the recesses of said first socket members, leg members movably mounted in the recesses of said additional socket members, and means whereby the head, arm members and leg members are adjustably connected with said body.

6. A doll comprising a hollow collapsible body provided with a neck opening and arm and leg openings, a rigid supporting device located interiorly of said body and consisting of a back-bone section extending lengthwise of said body, a combined shoulder and chest section provided with concave arm recesses in registry with said arm openings, and a pelvis section provided with concave leg recesses in registry with said leg openings, said supporting device being in molded connection with said body, a neck member provided with a bearing surface exteriorly of said body and extending through said neck opening into connection with said device and provided with an annular recess, a neck portion comprising an integral extension of said body at said neck opening extending into said annular recesses whereby said neck member and said body are connected with each other, a head movably mounted on the exterior bearing surface of said neck member, arm members movably mounted in said arm recesses, leg members movably mounted in said leg recesses, and means whereby said head, arm members and leg members are adjustably connected with said body.

7. A doll comprising a hollow collapsible body provided with a neck opening and arm and leg openings, a rigid supporting device located interiorly of said body and consisting of a back-bone section extending lengthwise of said body, a combined shoulder and chest section provided with concave arm recesses in registry with said arm openings, and a pelvis section provided with concave leg recesses in registry with said leg openings, said supporting device being vulcanized to said body for intimate connection therewith, a neck member provided with a bearing surface

- exteriorly of said body and projecting inwardly through said neck opening into connection with said rigid device, a head movably mounted on the exterior bearing surface of said neck member, 5 arm members movably mounted in said arm recesses, leg members movably mounted in said leg recesses, and means whereby said head, arm members and leg members are adjustably connected with said body.
- 10 8. In a doll, a hollow collapsible member of soft rubber provided with a spherical end constituting a joint and having an opening, a spherical supporting device within said spherical end for internally supporting the same against collapse, 15 said spherical device being in molded, vulcanized connection with said spherical end and having a recess and a continuing aperture, and a fastening device connected with said spherical device and slidably mounted in said recess and continuing aperture, said fastening device being initially located entirely within said spherical end and being adjustable into a position of accessibility 20 through said opening.
9. In a doll including a body provided with an external bearing at the neck thereof, that improvement which comprises a hollow collapsible head of soft rubber provided with eye-sockets and a bearing portion adapted for engagement with the external bearing of said body, a hollow 25 supporting means within said head for supporting predetermined portions of said head from the inside and extending downwardly into proximity with said bearing portion for imparting rigidity to said head at the bearing portion thereof, said supporting means being open at the front and sides in registry with the face and cheeks 30 of said doll, and eye mechanism movably car-
- ried by said supporting means and including eyes located in registry with said eye sockets.
10. In a toy figure including a body, a head and recesses for accommodating limb members, that improvement which comprises a limb member of moldable material provided with a collapsible hollow spherical end having a restricted opening therein, said spherical end constituting a joint adapted to fit one of said recesses, a rigid supporting device in conforming interior surface engagement with said spherical end and enclosed thereby for supporting said spherical end against collapse, and fastening means movably carried by said supporting device in registry with said opening for adjustment in its entirety into said spherical end and into an operative position through said opening for connecting said limb member with said body.
11. In a doll including a body, a head mounted thereon, and bearing recesses for accommodating arm and leg members, that improvement which comprises a hollow collapsible member of soft rubber provided with a hollow spherical end constituting a joint adapted to fit into one of said bearing recesses and having a restricted opening, a spherical supporting device enclosed within said spherical end in conforming interior surface engagement therewith for supporting said spherical end against collapse, fastening means slidably carried by said supporting device in registry with said opening and adjustably accessible therethrough for connecting said member with said body, and a metallic bearing shell secured to said spherical end in external relation thereto for bearing contact with the surface of the co- 105 operating recess.
